UNITED STATES PATENT OFFICE.

ELMER H. BOTTERBERG, OF AUBURN, INDIANA.

EXTENSIBLE SHADE-HANGER.

SPECIFICATION forming part of Letters Patent No. 576,540, dated February 9, 1897.

Application filed March 25, 1896. Serial No. 584,847. (No model.)

To all whom it may concern:

Be it known that I, ELMER H. BOTTERBERG, a citizen of the United States, residing at Auburn, in the county of De Kalb, in the State 5 of Indiana, have invented certain new and useful Improvements in Extensible Shade-Hangers; and I do hereby declare that the following is a full, clear, and exact description of the invention, which will enable others skilled in the art to which it appertains to 10 make and use the same, reference being had to the accompanying drawings, which form part of this specification.

My invention relates to improvements in 15 extensible shade-hangers.

The object of my invention is to provide an extensible and adjustable hanger for shade-rollers so constructed as to be fixed upon the upper sash in such a manner as to be movable with the sash as it is raised and lowered 20 for purposes of ventilation, and so arranged as to be readily extensible to suit any width of window or window-shade, and so arranged as to be laterally adjustable for any depth of 25 window-jamb.

My invention consists of two interlocking and extensible sections having upon their outer ends integral shade-roller supports, and a pair of extensible and adjustable hanger-brackets adapted to be fixed on the window-sash and to support the said extensible sections.

The novel feature of my invention consists in the means for securing both a longitudinal extension and a lateral adjustment of the shade-hanger without detaching the hanger-brackets from their fixed position on the sash.

In the accompanying drawings similar reference-numerals indicate corresponding parts 40 in all the views.

Figure 1 is a perspective view of my improvement in position upon a window-sash with the curtain roll or shade arranged therein, but broken away in parts. Fig. 2 is a rear 45 perspective of my invention, showing an enlarged view of the interlocking extensible sections and the manner of connecting the same with the hanger-brackets. Fig. 3 is a detail of 50 one of the extensible hanger-brackets, showing the arrangement of the slidable section thereof and its supporting and interlocking flange.

All parts of my improvement are preferably made of sheet metal.

The two-part hanger is made of the sections 3 and 5 of approximately equal length, having upon their outer extremity the integral forwardly-projecting apertured lugs 4, Fig. 1, in which the shade-roller 6 is mounted.

The hanger-section 3 has its upper edge 60 folded upon itself rearwardly and then bent rearwardly, forming an open flange 7, Fig. 2, arranged at right angles with the body of the said hanger and adapted to slidably contain a similarly-constructed and correspondingly-arranged flange 8 on the interlocking section 5. The lower edge of the said hanger-section 5 is provided with a turned-up vertical flange 16, Fig. 1, arranged upon the front face of the said hanger and adapted to slid- 70 ingly contain the upturned lower edge 17 of the said section 3, Fig. 1. Thus constructed and arranged the said sections 3 and 5 are securely interlocked and can be disconnected only by withdrawing them endwise from their 75 engagement, and they are adapted for a ready and convenient extension or contraction of their length to suit the width of the window or of the shade-roller.

The hanger-brackets, by which the extensible two-part hanger is supported, are also formed of two sections.

The slidable sections 11 and 12, exactly alike in construction, have their forward portion first bent at right angles to the remaining portion thereof and then so folded upon itself as to give the forward ends 10 and 9, respectively, an upright position, Fig. 2, with their sides at right angles to the horizontal portion thereof. The upper end of the said 85 upright portions is provided with a rearwardly-projecting flange 15, on which the two-part hanger is supported in a manner hereinafter described. The fixed sections 8 and 7, respectively, of said brackets, also exactly alike, have their rear end bent in a right-angular flange 18, which is provided with two or more perforations for proper screws to secure said sections to the window-sash. They also have their lower edge turned 90 upwardly, forming an open flange 14 for securing the lower edge of the said slidable section. The upper edge of the said fixed section is also provided with a right-angular 95 100

flange having its forward end bent downwardly to form a holding-flange 13 for the upper edge of the said slideable section, Fig. 3. The rear end of the said flange is bent 5 downwardly and overlaps the said flange 18 and has a registering holding-screw perforation therein. When the said sections 11 and 12 are thus mounted in the said fixed sections 8 and 7, respectively, they are longitudinally adjustable therein and are secured 10 against displacement by the said retaining-flanges 13 and 14.

My improved shade-hanger is thus constructed without the use of either solder or 15 joints of any kind in any of its parts, is cheaply made of any suitable sheet metal, and has small liability of getting out of repair.

The manner of using my improvement thus 20 described is briefly stated as follows: The said hanger-brackets are first rigidly fixed upon either the top or side rails of the upper window-sash by proper holding-screws. The hanger-sections are then united in their 25 interlocked position and adjusted to their desired extension to suit the width of window or length of shade-roller employed, and are slidingly mounted on said brackets by arranging the flange 15 of said brackets in the 30 open flanges 7 and 8. The said extensible hanger-brackets are then adjusted to suit the depth of the window-jamb, and the curtain-roll is then placed in position therein.

It is obvious that by the use of my improvement the curtain is raised and lowered with 35 the window-sash on which it is mounted, thereby removing it as an obstacle to proper ventilation. It is also obvious that the said hanger-brackets can be fixed with equal facility 40 upon either the top or side rails of the sash, and that they can be longitudinally adjusted at pleasure without detaching them from the extensible hanger or removing the curtain-roll.

Having thus described my invention and 45 the manner of employing the same, what I claim, and desire to secure by Letters Patent, is—

1. In a shade-hanger, an extensible and 50 adjustable bracket in two parts, one being a

fixed section having its rear end bent at right angles with perforations for securing it to the window-sash by nails or screws, and its lower edge turned upwardly thereby forming an open flange 14, and its upper edge provided 55 with a right-angled flange having its forward end bent downwardly to form a holding-flange 13, and the other section having its rear portion adapted for an adjustable sliding engagement within said flanges 13 and 14 and having 60 its forward portion bent at right angles to the remaining portion and then folded upon itself, so as to give the forward end an upright position, with the side at right angles with the horizontal portion thereof, and the upper end 65 of said upright portion having a rearwardly-projecting flange for engagement with the upper flange of a curtain-hanger for supporting the same all arranged as shown and described and for the purpose stated. 70

2. In a curtain-shade hanger, an extensible and adjustable bracket in two parts, one being a fixed section having its rear part bent at right angles, with perforations for securing it to the window sash or casing by nails 75 or screws, and its lower edge turned upwardly, thereby forming an open flange 14, and its upper edge provided with a right-angular flange having its forward end bent downwardly to form a holding-flange 13, and its 80 rear portion adapted for an adjustable sliding engagement within said flanges 13 and 14, and its forward portion bent at right angles to the remaining portion and then folded upon itself so as to give the forward end an upright 85 position with the side at right angles, with the horizontal position thereof, and the upper end of the said upright portion having a rearwardly-projecting flange for engagement with the upper flange of a two-part curtain-hanger 90 for supporting the same, in combination with the two-part hanger 3 and 5 and all arranged as described and shown.

Signed by me at Auburn, De Kalb county, State of Indiana, this 23d day of March, A. D. 95 1896.

ELMER H. BOTTERBERG.
